PRESSURE-OPERABLE LIQUID DISPENSING APPARATUS

Edward J. Poitras, Holliston, and John F. Taplin,
West Newton, Mass.

Application March 25, 1950, Serial No. 151,888

3 Claims. (Cl. 222—209)

1

Our present invention relates to the dispensing of liquids including those of relatively high viscosity, especially in determined use-unit volumes and under a substantially drip-free cut-off action. More particularly the invention aims to provide remotely operable liquid dispensing apparatus, actuatable without use of or contact with the user's hands, and capable of handling highly viscous fluids, by reason of ejection under pressure, while avoiding after drip at the delivery point, by a draw-back or sucking action effective thereto.

The several novel features and advantages of our invention will more fully appear from the following description taken in connection with the accompanying drawings of one illustrative embodiment, in which:

Fig. 1 shows the apparatus as a whole, with the dispenser proper in vertical section;

Fig. 2 is a corresponding view on a larger scale of the ejector unit of Fig. 1, with the parts in shot-delivering position;

Figure 3 is a top plan, on a reduced scale, of the liquid vessel with the delivery end of the dispensing tube broken away;

Fig. 4 is a top plan of the pressure initiator; and

Fig. 5 is a partial section as on the line 5—5 of Fig. 4 showing an air inletting check valve in normal closed position.

Liquid soap and similar dispensers have heretofore been characterized by a tendency to dispense varying uncontrolled volumes, often in excessive amounts. Excessive drip or discharge for an indefinite period after use, resulting in wasteful and unsightly residue, has been common, particularly where fluids of relatively high viscosity have been used with dispensers employing gravity discharge. Generally manipulation by one or both hands has been required, making for wasteful spillage and necessitating that the user's hand or hands contact the dispenser. Consequently such prior dispensers become dirtied and contaminated in use, as by a surgeon with his hands and arms messed to the elbow after an operation, or by a mechanic leaving a greasing job. These objections are overcome by the apparatus of our invention.

Referring to the drawings in more detail, our novel dispenser comprises a container or vessel 10 which may be generally cone or goblet shaped, as shown, and may be relatively thin-walled to afford a liquid reservoir 11 of maximum volume for the given size of vessel. The latter may be fashioned as by molding from any durable mate-

rial impervious to the soap or other fluid, as metal, glass or plastic. A removable cover or cap 12 seating on the container rim seals the reservoir, a lapping annular flange 13 desirably preventing sidewise displacement.

At the front or dispensing side of the vessel 10 an upper portion of the wall is enlarged or thickened to form a nose 14 having a supporting aperture 15 for the discharged tube 60 to be referred to. The cover 12 has a matching enlargement 14a recessed at the under face as at 16 to seat over the projecting end of a set screw 17 in vertical line with the discharge tube. This screw serves both to hold the latter removably and adjustably and also as an aligning stop for the cover, preventing turning of the latter in the seated position.

For wall mounting the vessel 10 is provided with integral or other lugs or bracket engaging members 18 preferably at the side opposite the nose 14. Desirably these mounting lugs incline downwardly and toward each other for wedging reception by a conforming bracket 19. The latter may be fixed to a wall or other support in any convenient manner, as by screws 19a.

A fluid-pressure hydraulic or pneumatic metering and ejecting assembly 20 incorporating a unit-volume measuring and dispensing chamber is mounted at the central bottom portion of the vessel. It comprises oppositely disposed upper and lower body members or sections 21 and 22 each including a cylinder 23, 24, a circumferential coupling flange 25, 26 at the mating ends, and a reduced stem or neck 27, 28 at the opposite ends. These two sections 21 and 22 are detachably fixed together as by a series of bolts 25x. The cylinders 23, 24 are formed with aligned axial bores 23a, 24a of calculated diameter terminating inwardly in oppositely flaring central enlargements which together define a cavity or main chamber 30. The bore 23a of the upper section 23 is stepped at the juncture with the cavity 30 to provide a downfacing seating recess 29.

Between and held by the joining flanges of the body sections 21, 22 is a flexible diaphragm 33, which may be of a resilient plastic or rubber-like sheet material or other construction affording it substantial capacity for deflection transversely to its plane of support. This diaphragm 33 operatively divides the cavity 30 horizontally into an upper or dispensing chamber 31 and a lower or actuating chamber 32, while also serving as a peripheral seal for the two body sections 21, 22 of the unit.

The dispensing chamber 31 is filled from the

reservoir 11 through an inlet 35 in one of the flanges, here shown in the lower flange 26, communicating through a small aperture 33a in the diaphragm 33 with a radial passage or groove 36 leading to the region of the recess 29 above mentioned. As indicated in Figs. 1 and 2, the passageway 36 is formed for minimal interruption of the under face of the upper flange 25, preventing lifting of diaphragm 33 in the vicinity of the inlet 35. The latter has an intermediate enlargement defining a valve chamber 37 with an upwardly facing valve seat 38. A ball valve 39 is confined in the valve chamber 37, normally seating at the bottom thereof in the closed, chamber-sealing position as in Fig. 1.

It will be seen that fluid from the reservoir 11 entering at the inlet 35 will fill the dispensing chamber 31 and other communicating space above the diaphragm 33. The latter is normally depressed toward or into contact with the bottom wall of the cavity 30 by the liquid weight and assisting spring means to be described; see Fig. 1. A unit-volume service, metered-shot or unit-shot of the liquid is determined by the extent of upward displacement of the diaphragm 33 in a dispensing operation. Outlet for the liquid is through a throttling orifice and check valve at the top of the dispensing chamber 31. There a valve plate 40 is fixed in the recess 29 mentioned, having a central outlet orifice 41 within a surrounding depression 42 providing a seat for a second and downwardly closing ball valve 45. The latter is confined in the cylinder bore or outlet valve chamber 23a of the upper body section 21. Thus upon upward displacement of the diaphragm 33 a proportionate quantity of the liquid in the dispensing chamber 31 above the diaphragm is forced upwardly through the outlet orifice 41, opening the valve 45 thereat. At the same time the pressure attendant on displacement of the diaphragm 33 acts to press the inlet valve 39 more firmly against its seat 38. Serrations, flutes or the like as at 23b, Fig. 1, may be provided at the juncture of the cylinder and stem bores 23a, 21a, permitting fluid flow even though the ball valve 45 is thrust to the top of the valve chamber, such flutes or like passage-defining formations preventing closure of the chamber by the valve.

For positively regulating and variably controlling the unit service volume, metered-shot or unit-shot of the liquid to be dispensed, means is provided for accurately determining the extent of diaphragm displacement. For this purpose there is centrally mounted at the upper face of the diaphragm 33 a stop or stop element 50, herein a cup-shaped member, adapted to come into limiting abutment with an opposite wall portion of the cavity 30, thereby defining the maximum displacement for the diaphragm 33. In the illustrated example the limiting engagement is had by the upturned flange portion 51 of the stop 50 abutting the cavity top wall adjacent the outlet valve plate 40. The stop 50 herein being of somewhat greater diameter than that of the recess 29 which holds the valve plate 40, the engagement accordingly is around the edge of that recess, as shown in Fig. 2.

The volume-regulating stop 50 herein also serves as the bottom seat for the diaphragm spring return means, shown as a coil spring 55 bearing at its opposite upper and against the outlet valve plate 40. By adjusting the height of the contact portion 51 of the stop 50 the unit-shot, metered-shot or volume of liquid dispensed

at each actuation of the diaphragm may be accurately predetermined. For any given setting it will be uniform regardless of the force applied in displacing the diaphragm. For purposes of volume adjustment the stop 50 may be removably associated with the diaphragm for ready inter-exchange with different heights of stop or the diaphragm and stop may be formed as a replaceable unit; in other instances the adjustment being had by bending the contact portion 51 of the stop up or down to the desired extent.

The described metering and ejecting assembly 20 is installed within and at the base of the reservoir 11, at a mounting aperture 11x through which the threaded stem 28 of the lower body section 22 extends, with suitable interposed gasketing if desired. A seating shoulder 24b at the base of the lower cylinder 24 fits snugly against the reservoir wall at the mounting aperture 11x. An outside lock nut 28x turned up onto the projecting threaded stem 28 anchors the assembly in operative position.

The fluid dispensed passes up through a reduced bore 27a in the stem 27 of the upper body section 21, leading from the outlet valve chamber 37, and through an adjustable length of preferably flexible tubing 59 within the reservoir 11. This tubing is fitted at the lower end onto the nipple-like upper end of the stem 27 and at the upper end coupled tightly over the inner end of a rigid dispensing tube 60 terminating outside the reservoir in a down-turned spout 61. This dispensing tube and spout element 60, 61 extends out through the bearing aperture 15 therefor in the vessel nose 14 where it is held with capacity for projective adjustment by the set screw 17 earlier mentioned.

From the foregoing it will be understood that the metering dispenser of the invention is peculiarly adapted for fluid-pressure operation, which term is intended to include both hydraulic and pneumatic means, and likewise for operation from substantially any desired location, whether directly by an individual user operating a treadle or other manual control conveniently adjacent the dispenser, or otherwise from more or less remote locations. The invention accordingly comprises, in combination with the pressure-operable dispenser device, means for applying actuating pressure to the diaphragm 33. For this purpose we have herein in Figs. 1 and 4 illustrated a remote-controlled actuator means operatively associated with the dispenser, claims for which, as of general utility, are contained in another application.

Referring to Figs. 1 and 4 such remote-operable actuator means comprises a treadle or manually deformable pad-like compressible element 70. This is herein constructed as a resilient-walled bag or pouch shown as generally rectangular in plan, with a flat supporting face or bottom 71 and somewhat rounding top or front face 72, in the normal filled condition. This hollow pad or force-receiving element 70 may be integrally molded or otherwise formed of any suitable flexible wall-forming material capable of supporting a fluid seal and of a tough wear-resistant character adapting it for example to be placed on the floor for depressant operation by the user's foot. Suitable materials may readily be selected such as various rubber and rubberous compositions and certain of the commercially available synthetic resins and molding com-

pounds. The foot-engaged surface may be reinforced by ribbing as at 72a, Fig. 4.

A relatively rigid block or plate 75 is integrally or otherwise secured and sealed in closing relation to an end wall or mouth of the hollow pad 70. This block 75 has cast or otherwise fixed in it a connector nipple 76 providing a passage 77 communicating with the interior of the pad, the nipple including an outer threaded attaching portion 78. One end of a plastic, copper or other flexible tubing 80 of any desired length is expanded over the free end 78 of the nipple 76 and secured to it by a surrounding threaded coupling sleeve 81 turned up onto the nipple. The other end of the tubing 80 is demountably installed at the projecting lower tapered end of the stem 29 of the lower body section 29 of the metering ejector assembly 20. This tubing 80 is held in pressure-tight union with the stem 28 by a threaded coupling sleeve 82 generally similar to that at the nipple 76 of the pad 70. One or more holes 76a desirably are provided in the pad block 75 for receiving screws or other anchor means 75b whereby the pad 70 may be immobilized by attachment to the floor or other support at the point of operation.

It will be seen that the pad 70 and the connecting tubing 80 together with the axial passage and cavity portion in the lower body section 22 below the diaphragm 33 constitute a normally closed hydraulic system or cell adapted to contain a pressure-transmitting fluid medium such as a fluent oil, or it may be air. In the instance of air as the hydraulic fluid or pressure medium it is desirable to provide for automatic replenishment, in the event of some leakage under the application of pressure. Accordingly, as shown in Fig. 5, the nipple 76 may be provided in its exposed portion, illustrated as non-circular or hex-shape for gripping, with a stepped radial passage 79 forming a chamber for a ball or other inlet check valve 79a, normally urged by the actuator pressure outward against a tubular seat 79b. The latter may be formed as a plug pressed into the outer end of the passage 79 after the ball is inserted. The upper end wall of the chamber 79 is nicked as at 79c to prevent the ball valve 79a from sealing thereat.

When appropriately filled with the pressure medium the system will transmit to the diaphragm 33 as a displacing force thereat whatever pressure is applied to the compressible pad 70. Thus the operator by stepping on or otherwise deforming the pad 70 will impress on the hydraulic system a pressure which will be effective at the diaphragm 33 to oppose spring 55 and displace the diaphragm 33 upwardly in the cavity 30, moving it from the base of the actuating chamber 32 of the cavity toward or into the overlying dispensing chamber 31 thereof. Thus the cavity volume above the diaphragm 33 is reduced by an amount determined and limited by the engagement of the stop 50 with the opposite wall. This displacement creates and defines a single dispensing charge or shot, of predetermined volume, referred to herein as a "metered-shot" or "unit-shot." By reason of the limited uniform displacement available for the diaphragm 33 the volume of a single shot will remain constant regardless of how long, short, strong, or weak the depressant force on the pad or foot-operated element 70 may be, provided only that it is enough to overcome the static pressure of the relatively weak spring 55 and the liquid above the diaphragm. In other words, a

sudden impulse of pressure from the treadle, having a fixed time-pressure relationship, is not necessary to the functioning of the device.

Attendant upon a pressure shot, ball valve 39 is pressed firmly against its seat, thus leaving only the passage 23a for escape of the detergent or other liquid. There the other valve 45 is unseated and permits the flow of one unit volume or metered shot to the dispensing tube 60. On release of the pressure on the pad actuator 70 the spring 55 moves the diaphragm 33 back down in the cavity 30 to its normal depressed position therein, the resilient pad 70 at the same time resuming its initial configuration, as in Fig. 1. As noted, where a low density fluid, such as air, is used in the actuator system, minute leakage may occur particularly during the pressure stroke, resulting in gradual volume decrease in the treadle. This loss is compensated for by the admission of air past the check valve 79a, Fig. 5, which is unseated by the suck-in effect at seat 79a caused by pad 70 in reverting to its normal fully expanded position when relieved of pressure and following the return of diaphragm 33.

As the volume of the upper or dispensing chamber 31 of the total cavity 30 is restored to its original figure the attendant internal pressure drop in the cavity produces an action of inspiration, with a suck-in or draw-back effect at the spout 61 as well as at the cavity inlet 35. There the ball valve 39 unseats to refill the dispensing chamber 31 from the reservoir 11, while the outlet and sealing valve 45 seats to retain a column of the liquid in the tubing connection and dispensing tube 59, 60. This inspiration positively withdraws and retains the liquid within the spout 61, preventing any drip thereat. The amount of fluid drawn back into the tube 60 may be determined, for a fluid of given viscosity and density, by the selection of appropriate valve 45 and valve chamber 23a diameters, and valve density. It should be noted that our novel construction is self-compensating, in that when fluids of higher viscosity and greater tendency to after-drip are used, the valve is raised higher in the chamber, producing a greater inspiration effect. It will be realized that by reason of the coincident seating and unseating of the valves 39, 45 a rebalancing of pressures is had at the inlet and outlet passages 35, 41 of the metering and dispensing chamber 31. The dispensing tube thus remains filled with the liquid, so long as a supply thereof remains in the reservoir 11 above the level of the chamber inlet 35. Any subsequent compression of the pad 70 will consequently dispense at the spout 61 exactly the volume displaced from the dispensing chamber 31. When the dispenser is first placed in use a few initial empty shots will pump the liquid through the dispensing chamber and to the tubing 59, 60 until the latter is filled.

As indicated in connection with the brief description of the several views of the drawings and elsewhere herein, the particular structure shown while representing a presently preferred embodiment is intended as exemplary of various equivalent constructions adaptable to the purposes of the invention and is susceptible of a substantial range of modification in such respects as the size, shape and other aspects of the fluid supply vessel, the construction and arrangement of the movable wall, shown as a diaphragm, which provides for corresponding volume expansion and reduction at the opposite sides thereof, the type of valves employed where-

by the inspiration and drip counteracting effects are had with self-compensating capacity in that regard as to all viscosities of fluids to be handled, and the structure of the associated pressure actuator system or device.

Accordingly it will be understood that our invention is not limited to the particular embodiment thereof illustrated and described herein, and we set forth its scope in our following claims.

We claim:

1. A "metered shot" liquid dispenser for detergent and other fluids comprising a liquid reservoir of cup form closed at the bottom save for a relatively small valve-mounting and pressure-admitting aperture and having a top closure, the reservoir having a dispensing conduit from the interior to an external discharge point, and a hydraulic, aspirating and shot-measuring pump unit bodily removably installed at the bottom aperture of the reservoir, said pump unit comprising a body having oppositely disposed upper and lower sections with lateral coupling flanges and defining between them a shot-measuring and ejection cavity and holding between them a cavity-dividing fluid-sealing diaphragm, the lower body section having a shoulder for seating on the reservoir bottom wall around the aperture therein and having a reduced neck demountably secured in outwardly projecting position at the aperture and adapted for connection with an hydraulic pressure-supplying conduit, spring means in said cavity above and normally depressing the diaphragm, the upper body section having an outlet bore extending from the cavity and connected with the dispensing conduit, an inlet passage in the pump body communicating between the reservoir and the cavity portion which is above the diaphragm, and oppositely operating inlet and outlet valves in said inlet passage and outlet bore respectively operable upon pressure application on the diaphragm to close off the cavity from the reservoir and to pass a measured shot of liquid to the dispensing

conduit, the outlet valve being operable immediately on release of such pressure to effect a drip-retaining inspiration at the discharge end of the dispensing conduit.

- 5 2. A "metered shot" liquid dispenser for liquid soap, detergents, and other liquids, comprising a reservoir for the liquid, a pressure-actuated ejector unit in the reservoir and containing interacting ejection and actuating chambers with a common movable wall separating them, the ejection chamber having an inlet for liquid from the reservoir and an outlet with a dispensing tube connected thereto, and automatic oppositely acting valves for the inlet and the outlet respectively, the outlet valve including a valve chamber and a valve member movable therein to and from closing position, said chamber and valve member constructed, proportioned and arranged to afford capacity for augmented movement of the valve member out of closing position providing a calculated period of inspiration during reverse closure thereof adequate to effect drip-preventing draw-back of the liquid at the free end of the dispensing tube, the extent of said inspiration being automatically self-adjusting as appropriate to the viscosity of the liquid by directly proportionate extent of valve movement.
- 10 3. A "metered shot" liquid dispenser according to claim 2 wherein the outlet valve chamber has passage-defining formations at the outlet preventing closure thereof by the valve under maximum augmented movement thereof from closing position.
